SADDLE

Roland W. Faulhaber, Elyria, Ohio, assignor to
The Troxel Manufacturing Company, Elyria,
Ohio, a corporation of Ohio

Application June 19, 1935, Serial No. 27,312

13 Claims. (Cl. 208—15)

This invention relates to cycles and the like saddles, and more particularly to a saddle of this type provided with a built-in compartment at the rear of the saddle.

5 Prior saddles of this type with which I am familiar have had an independent container for tools and the like suspended from the saddle, but detract from the appearance of the saddle, and additionally the continual swinging of the container when the cycle is in motion causes an undesirable noise due to intermittent contact of the articles in the container.

10 I have devised a saddle for cycles and the like provided with a built-in container at the rear of the saddle, without substantial alteration of the conventional saddle contour and which can be provided for relatively little increase in the cost.

15 It is a primary object of my invention, therefore, to provide a saddle of conventional contour having an article compartment incorporated therein.

20 Another object of my invention is to provide a cycle or the like saddle having an article compartment incorporated therein, and provided with improved means for locking the closure portion of the container.

25 Another object of my invention is to provide a saddle of the above type having an article container incorporated therein, and wherein the handle means effecting locking of the closure portion of the container also functions as a reflecting element.

30 Another object of my invention is to provide a saddle of the above type having an article container incorporated therein, which can be economically manufactured.

35 Other objects of my invention and the invention itself will become increasingly apparent from a consideration of the following description and drawing, wherein:

40 Fig. 1 is a longitudinal view partially in section of a preferred embodiment of my invention;

Fig. 2 is a rear elevational view of the embodiment of Fig. 1;

45 Fig. 3 is an enlarged fragmentary view of a modification of my invention.

Fig. 4 is a sectional view taken on the line 4—4 of Fig. 1.

45 Referring now to the drawings, I have indicated generally at 10 a saddle seat resiliently mounted on a reach member 11 and springs 12. The reach member and springs constitute no essential part of my invention, and any suitable means for resiliently securing the seat 10 to a cycle post or support may be employed.

50 I have illustrated the seat 10 as comprising a cover portion 13 and a base portion 14 enclosing suitable cushioning material and/or stiffening means, the cover and base portions being suitably joined at their peripheral portions. Although I

have illustrated the seat 10 as being formed of leather, I contemplate that a suitably molded rubber seat may be used.

5 The lateral walls of the seat are preferably of increasing depth proceeding from the pommel with the rear wall being formed to provide a peripheral portion 15 upwardly concave, as best illustrated in Fig. 2. The peripheral portion 15 of the rear wall of the saddle is preferably reinforced by binding material 15', which may be of 10 a color contrasting with the general color of the saddle to lend a distinctive appearance thereto.

The springs 12 are disposed a substantial distance forwardly of the rear wall of the saddle, and a member 16 of flexible material is secured to the 15 base or underside of the seat transversely thereof and adjacent the springs 12 and also to the inner face of the lateral or side walls of the seat. The lower part of member 16 is bent to extend in a rearward direction and is secured to a peripheral 20 portion of the side walls rearwardly of the spring 12, as indicated at 17.

A generally U-shaped and relatively stiff closure element 18 is hingingly secured to the seat adjacent the juncture of the peripheral portion 25 15 of the rear wall and the lower edge of the side walls, as indicated at 19, preferably by providing a binding strip of suitable material as indicated at 20 for peripheral portions of the side walls and continuing the same to form a binding strip for 30 the lower peripheral portions of the closure element 18, although any suitable means hingingly securing the closure element 18 adjacent its lateral extremities to the seat may be used.

It is understood that the material of the binding strip is sufficiently flexible to permit this hinging action.

A binding strip may also be provided for the upper or U-shaped peripheral edge of the closure element 18.

40 The base portion of the compartment formed by the material 16 is extending rearwardly and secured to the lower edge of the closure element 18, preferably by the binding strip hereinbefore described. The closure element 18 is also preferably of arcuate form transversely so as to give the appearance of a conventional saddle to the rear wall when the element 18 is in closed position.

45 The means for locking the closure element to 50 form a closed article compartment will now be described. Secured generally centrally of the rear of the saddle is a plate formed with a depending loop 22, the plate being secured in any suitable manner, as by riveting.

55 A hook element 23 is manually operable to engage the loop 22 and is mounted by perforating the closure element 18 and projecting therethrough a threaded stem 24 formed with an enlarged integral head 25 disposed rearwardly of 60

the closure element 18. The stem 24 adjacent the head 25 may be provided with an enlarged portion spacing the head 25 from the element 18 to facilitate gripping of the head.

5 Lock nuts 26 threadedly engage the stem 24 on either side of the hook 23 and tightly grip the element 23 therebetween, whereby rotation of the head 25 will actuate the hook element 23 to engage the loop 22 and lock the closure element 18 in closed position.

10 The head 25 may comprise a reflecting element formed of colored glass or the like and gripped by an annular flange provided on the head, adding to the safety of the cyclist and providing a convenient method of mounting such a signaling means.

15 I have illustrated in Fig. 3 a modification of my invention generally similar to the embodiment described but wherein the hook 23 is replaced by a resilient locking element 30 secured directly to closure element 18, having an end portion adapted to ride over loop 22 to lock the element 18 with the saddle to form a closed compartment. The closure element 18 may be opened 20 by an outwardly directed pull on the handle.

25 Although I have shown and described modifications of my invention, I contemplate that numerous and extensive departures may be made therefrom without departing from the spirit of 30 my invention and the scope of the appended claims.

Having thus described my invention what I claim is:

1. A cycle or the like saddle comprising rear 35 and lateral walls, a portion of the rear wall being movable hingingly outwardly and adapted to be lockingly secured to an adjacent rear wall portion, and flexible material secured to the under side of the saddle generally transversely thereof, and to the lateral walls, and adjacent 40 the base of the hinging rear portion to form a closed compartment with the hinging portion in closed position.

2. A saddle for cycles and the like comprising 45 rear and side walls and a seat, a portion of the rear wall being formed arcuate upwardly, and another portion complementary therewith forming a normally appearing rear wall portion and hingingly secured to the rear wall at laterally spaced points, flexible material secured to the 50 underside of the seat, and to the side walls, and to the said hingingly secured portion to form a compartment forwardly of the hingingly secured portion, and means associated with the rear wall 55 and the hinging portion whereby they may be lockingly secured.

3. The saddle as described in claim 2 wherein the locking means comprises a loop secured to the rear wall and a hook element operable by a rearwardly projecting handle secured to the hinging portion and engageable to maintain the hinging portion in closed position.

4. A saddle for cycles and the like comprising 65 depending side and rear walls, a substantial portion of the rear wall being hingingly movable, flexible material secured to the base of the movable rear wall portion, to the under side of the seat, and to the side walls to form a compartment with the movable rear wall portion forming 70 a closure element, and a handle associated with said hinging portion to lock the same in closed position.

5. The saddle as described in claim 4 and wherein said handle projects rearwardly from the hinging portion and comprises a colored reflecting surface forming a signalling means.

6. In a cycle or like saddle of the type comprising a seat portion and a wall portion depending therefrom, means providing a receptacle under the seat portion, an opening in the wall portion, and a hinged door therefor giving access to the receptacle. 10

7. In a cycle or like saddle of the type comprising a seat portion and a peripheral wall portion depending therefrom, means providing a receptacle under the seat portion, an opening in the wall portion, and a hinged door therefor giving access 15 to the receptacle.

8. In a cycle or like saddle of the type comprising a seat portion and a wall portion depending therefrom, means providing a receptacle under the seat portion, an opening in the wall 20 portion, and a hinged door therefor giving access to the receptacle, the door having a closed position in which it constitutes part of the wall portion.

9. In a cycle or like saddle of the type comprising a seat portion and a peripheral wall portion depending therefrom, means providing a pocket-form receptacle under the seat and within the depending wall portion, a part of the wall portion being hingingly supported and normally 30 closing the pocket mouth, and being outwardly hingingly movable to open the pocket to give access thereto. 25

10. A cycle or like saddle of the type comprising a seat portion and a wall portion depending 35 therefrom, means providing a receptacle under the seat portion, an opening in the wall portion, closure means for said opening permitting access to the receptacle and forming a portion of the wall in closed position. 40

11. A cycle or like saddle of the type comprising a seat portion, a wall portion depending therefrom, means providing a receptacle under the seat portion, an opening in the wall portion, and closure means for said opening permitting 45 access to the receptacle, the closure means in closed position abutting peripheral wall portions forming the opening and complementary therewith forming a continuous wall of normal contour.

12. A cycle or like saddle of the type comprising 50 a seat portion, a wall portion depending therefrom, means providing a receptacle under the seat portion, an opening in the wall portion, closure means for said opening forming a portion of the wall in a closed position and with 55 peripheral portions of the closure means and wall in abutting relation, and locking means comprising interengaging elements on the closure means and wall adapted to maintain the said portion of the wall and closure means in abutting 60 relation.

13. A cycle or like saddle of the type comprising 65 a seat portion, a wall portion depending therefrom, means providing a receptacle under the seat portion, an opening in the wall portion, and closure means for said opening restoring the normal contour of the wall when in closed position and movable outwardly from the wall permitting 70 access to the receptacle. 70

ROLAND W. FAULHABER.
